UNITED STATES PATENT OFFICE.

CARL POHLIT, OF ESSEN, GERMANY, ASSIGNOR TO FRIED. KRUPP, OF SAME PLACE.

SAFETY LOCKING DEVICE FOR GUNS.

SPECIFICATION forming part of Letters Patent No. 624,680, dated May 9, 1899.

Application filed December 31, 1897. Serial No. 665,060. (No model.)

To all whom it may concern:

Be it known that I, CARL POHLIT, a citizen of the German Empire, residing at Essen, Germany, have invented new and useful Improvements in or Connected with Safety Locking Devices for Guns with Wedge-Type Breech-Closing Mechanism, (for which I have obtained Letters Patent in Germany, No. 97,930, dated February 26, 1897; in Austria, No. 10 47/5,066, dated November 27, 1897; in France, No. 270,567, dated September 18, 1897; in Belgium, No. 130,713, dated September 18, 1897; in Italy, Reg. Gen., XXXIII, 46,195, Reg. Att., XC, 170, dated December 31, 1897; 15 in Spain, No. 21,564, dated November 16, 1897; in Sweden, No. 8,909, dated October 23, 1897; in Norway, No. 6,154, dated October 29, 1897; in Switzerland, No. 15,282, dated October 21, 1897, and in England, No. 26,990, dated November 18, 1897,) of which the following is a specification.

My invention has reference to improvements in horizontal wedge-fermetures of guns in which the hammer is cocked by a double- 25 armed cocking-lever actuated by the lock-screw when the latter is turned for unlocking the fermeture.

The invention consists in a safety device which at the same time prevents opening of 30 the breech and firing.

The nature of my invention will best be understood when described in connection with the accompanying drawings, in which—

Figure 1 represents a side view of the breech-block locked, but not secured. Fig. 35 2 is a horizontal section on the line 2 2, Fig. 1, locked and hammer cocked. Fig. 3 is a horizontal section on the line 3 3, Fig. 1, hammer cocked. Fig. 4 is a side view of the 40 breech locked and secured. Fig. 5 is a horizontal section on the line 5 5, Fig. 4, fermeture locked and secured, hammer held at rest. Fig. 6 is a vertical section on the line 6 6, Fig. 1, seen from the left. Figs. 7 to 11 45 are detail views.

Similar letters of reference designate corresponding parts throughout the several views of the drawings.

In the drawings, A is the breech-wedge; G, 50 the lock-screw, with the handle K and flange w; J, the hammer; H, the hammer-spring;

B, the cocking-lever; L, the trigger; M, the sear, and N the sear-spring.

The hammer is cocked in the usual manner—that is, in unlocking the breech-block 55 an inclined surface of the lock-screw acts against a correspondingly-formed surface of the cocking-lever B, Figs. 1 and 2. The gun is also fired in the usual manner by means of the trigger L, which, being turned on the bolt 60 h, causes its lug i to act against the flange k of the sear M so as to trip the cocking-lever.

F is a block inserted into the breech-block and held therein by the pivot-bolt h of the trigger, Figs. 1, 2, and 3. This block contains the sear M, with its spring N, and is also provided with a bore for the safety device, which latter consists of a bolt D with a semicylindrical extension d, Fig. 10, of a handle C, Fig. 11, attached to this bolt, and of a 70 spring E, Figs. 6 and 9. These parts are assembled in the following manner: The block F being removed from the breech-wedge, the spring E is first inserted into the bore of the block F, provided for the reception of the 75 safety device, so as to bear against a shoulder at the outer end. The bolt D is then inserted and pressed into the bore far enough that the socket t of the handle C can be passed over the square end of the bolt D and connected 80 therewith by a pin. The block F, containing the sear and safety device, is then again inserted into the breech-wedge M and secured therein by the bolt h.

On the safety-handle C there is a cylindrical shank c, and the breech-wedge has two rests v and u, Figs. 1 and 4, into either of which the shank c may be passed. When the handle C is in the position shown in Figs. 4 and 5, the shank c is within the rest v, bearing at the same time against a nose e, projecting from the flange w of the lock-screw G, thereby making it impossible to turn the breech-screw for unlocking the block. Furthermore, in this position of the handle the 95 semicylindrical extension d of the bolt D is opposite a lug a of the cocking-lever B, so that when the cocked hammer, Fig. 2, is released by pulling the trigger it cannot fly farther forward than to the position shown in 100 Fig. 5, the firing-point being held a short distance from the percussion-cap. Consequently

in this position of the handle C opening of the breech is prevented by the shank c and firing of the gun by the semicylindrical projection d.

5 It is evident that the lug a on the cocking-lever B may be arranged to allow the hammer any desired degree of forward motion. It may even be so placed that the extension d when in the safety position holds the hammer 10 cocked instead of allowing it to fly forward to the position of rest shown in Fig. 5.

From the position Fig. 1 (firing position) the safety-handle is changed to the position Fig. 4, (safety position,) and vice versa, by 15 pulling the handle until the shank c is out of its socket and then turning the handle to allow the shank c to snap into the other socket.

What I claim as new is—

1. In a horizontal wedge-fermeture of guns, 20 the combination with the breech-wedge, the lock-screw, the hammer, the cocking-lever and the trigger, of a safety device rotatably secured within the breech-wedge, a lug thereon engaging recesses in the wedge, whereby 25 in one of its positions it presents an obstacle to the motion of the lock-screw and also an obstacle to the motion of the cocking-lever, while in the other position both the lock-screw and the cocking-lever are released, substantially as described.

2. In a horizontal wedge-fermeture of guns, 30 the combination with the breech-wedge, the lock-screw, the hammer, the cocking-lever and the trigger, of a safety device rotatably

secured within the wedge, a lug thereon engaging recesses in the wedge, whereby in one of its positions it presents an obstacle to the motion of the lock-screw, and also an obstacle to further motion of the cocking-lever, when the firing-point of the hammer is a short distance from the percussion-cap; while in the other position, both the lock-screw and the cocking-lever are released, substantially as described.

3. In a horizontal wedge-fermeture of guns, 45 the combination with the breech-wedge A, the lock-screw G, the hammer H, the cocking-lever B with a lug a, and the trigger L, of a safety spring-bolt D inserted into the breech-wedge; said safety-bolt being provided with 50 a projection d; a handle C, and a shank c adapted to be inserted into and held within one or the other of rests u and v in the breech-wedge; the shank c, when within the rest v, bearing against a nose e on the flange w of 55 the lock-screw G, so as to prevent opening of the breech, while, at the same time, the projection d of the safety-bolt D is opposite the lug a on the cocking-lever B, and limits the forward motion of the hammer as desired, 60 substantially as and for the purpose specified.

In testimony whereof I have signed my name to this specification in the presence of two subscribing witnesses.

CARL POHLIT.
